ATTORNEYS

UNITED STATES PATENT OFFICE.

VILFREDO CABELLA, OF GUATEMALA, CENTRAL AMERICA.

SAFETY RAZOR.

Application filed November 20, 1923. Serial No. 675,902.

To all whom it may concern:

Be it known that I, VILFREDO CABELLA, a citizen of Italy, and a resident of Guatemala, Central America, have invented a new and Improved Safety Razor, of which the following is a full, clear, and exact description.

This invention relates to a safety razor, particularly of the type adapted to receive a double-edged blade.

An object of the invention is to provide a safety razor in which the blade holder can be rotated and is disposed at an angle to the handle so that the blade will always be in proper position and by its rotation can be reversed to present a fresh cutting edge.

Another object concerns the provision of means whereby the blade holder can be held by a latching means in the operative position but very easily released therefrom to be rotated.

A further object concerns the provision of means whereby the blade can be very quickly and easily removed from the holder and applied thereto.

A still further object concerns the provision of means whereby the parts are constructed in a simple and rugged manner, involving a minimum number of parts and a considerable economy in construction.

Another object concerns the provision of a construction whereby when one edge of a double-edged blade gets dull the other edge can be presented in the cutting position without removing it from the holder.

The invention is illustrated in the drawings, of which—

Figure 1 is a side elevation of the razor;

Fig. 2 is a front elevation;

Fig. 3 is a rear elevation;

Fig. 4 is a section taken on the line 4—4 of Fig. 2; and

Fig. 5 is an enlarged section taken on the line 5—5 of Fig. 4.

The form of the invention shown in the drawings is a preferred form, although it is understood that modifications in the construction and arrangement of the parts and in the character of the materials used may be adopted without departing from the spirit of the invention as set forth in the appended claims.

The preferred form of the invention shown in the drawings includes a handle

portion 1 having a reduced stem portion 2 at the upper end thereof which is bent as at 3 at an angle. The upper end of this stem has a reduced portion 4 threaded at 5. It is also provided with a shoulder 6. A sleeve 7 is adapted to fit over the upper end of the stem and rest against this shoulder. This sleeve at its upper end is tapered as at 8 and fastened by any suitable means, such as welding to a blade-holder plate 9 so that when the sleeve 7 is slipped over the upper end of the stem the blade holder is connected thereto. This assembly is held on the upper end of the handle by means of a clamping sleeve 11 interiorly threaded to engage the upper threaded end 4 of the handle, and provided with a tapered upper end engaging with the tapered upper end of the sleeve 7 to hold the sleeve 7 and the blade holder 9 on the end of the handle.

The engagement, however, of the clamping sleeve 11 with the blade-holder sleeve 7 is

only intended to be intimate enough to hold the blade holder in position but it is not tight enough to prevent the blade holder and the sleeve 7 from being rotated around the upper end of the stem 2. The upper end of the stem 2 is preferably inclined with respect to the rest of the stem at an angle of about 45°, so that the blade holder is correspondingly inclined at that angle; and by

reason of the fact that it can be rotated while on the stem opposite edges of the blade holder can be presented to the working position. The blade holder along its

opposite edges is provided with curved finger portions 12 and 13, of any suitable design similar to those now in use, to substantially guard the edges of the cutting blade as the razor is drawn over the face to effect

the result usual in safety razors, that is, to permit the blade only to meet the skin at the proper angle and eliminate danger of cutting.

Each of these dependent finger portions is provided with a pair of apertures 14 and 15 and the blade holder itself is provided with apertures 16 and 17 which, on the upper surface of the blade holder, are surrounded by annular ribs 18 and 19

adapted to receive the usual apertures in a blade disposed thereon so as to hold the blade firmly in position and prevent its sliding on the holder. The opposite side edges of the blade holder are provided with slots

90

95

100

105

20 and 21. The blade 22 on the holder is of proper dimensions so as not to extend over the slots.

When the blade is in position on the holder it is clamped thereon by reason of the fact that a blade-fastening plate 23 is placed over the blade. This fastening plate is provided with depressed ribs 24, 25 and 26 to bear on the blade at spaced intervals. Opposite ends of this blade fastening plate are provided with dependent ears 27 and 28. These ears are provided with shoulders such as 29. The main body portion of the ears depends from the ends of the fastening plate and pass through the slots 20 and 21, the shoulders 29 engaging the under surface of the ends of the blade-holder plate 9 to hold the ears in the slot and also hold the fastener plate firmly against the blade.

The handle portion is provided with suitable apertures into which the lower end of a pair of spring members 30 and 31 are introduced. These spring members intermediate their length are connected by a cross-bar 32 so that in the movement of these spring members they work together to cause a disconnection. The upper ends 33 and 34 of these spring members, which I choose to call latch members, pass through the respective pairs of holes 14 and 15 in the dependent finger portions of the blade holder, and by reason of this engagement hold the blade holder in a desired position. By reason of the fact that these members 30 and 31 are springy their upper ends can be disconnected from the holes 14 and 15 by pressing them inwardly, whereupon the blade holder can be rotated 180° so as to bring the new cutting edge into play. When this result is effected, the spring members are released so that their upper ends will engage with the other set of holes to hold the blade holder in a fixed position.

It will thus be seen that I have provided a construction simple, rugged and efficient, and economical to manufacture, whereby the blade holder on the upper end of a handle inclined at the proper relative angle can be latched in a definite position and easily released from said position so that it can be rotated to present a new blade in the working position and be immediately relatched.

This operation can take place without any necessity of removing the blade from the holder.

55

It is further obvious that I have provided a simple and efficient means whereby the blade can be quickly and easily clamped on to the holder and whereby it can be as easily removed therefrom by means of the construction and co-operation of the blade fastener plate with the blade and the blade-holder plate.

60

It is further obvious that I can readily disassemble the whole device by removing the blade-fastener plate, by taking the blade off the holder, by unscrewing the clamping sleeve 11 and removing the blade-holder plate sleeve 7. The springs 30 and 31 can readily be removed from the handle by merely pulling them out of their sockets. In this way the entire device can be taken apart readily to be cleaned or repaired or to replace any of the parts. The guard with which the blade-holder sleeve is engaged by the clamping sleeve 11 can be regulated by screwing up on the clamping sleeve 11 as desired.

70

What I claim is:—

1. A safety razor which includes a handle having a reduced threaded end, a shoulder and a blade-holder plate, a sleeve depending from said plate and adapted to be slipped over the end of the handle to rest on said shoulder, said blade-holder plate sleeve having a tapered upper end, and a clamping sleeve having a tapered upper end adapted to be slipped within the first-mentioned sleeve and threaded to engage with the threaded upper end of the handle, said clamping sleeve by reason of its taper adapted to hold the dependent sleeve on the blade-holder plate on to the handle whereby the blade-holder plate can be rotated on the handle while being firmly held thereon.

85

2. A safety razor having a handle, a blade-holder plate rotatably mounted on the upper end thereof, said plate having an aperture in each of its opposite sides, and spring means mounted on the handle, the upper end of said spring means adapted to project into either of said apertures to hold the blade holder in a definite position.
